Edwards, Sage & Power

UNITED STATES PATENT OFFICE.

ROBERT V. BINGAY, OF PITTSBURGH, PENNSYLVANIA, ASSIGNOR TO PITTSBURGH
TRANSFORMER COMPANY, A CORPORATION OF PENNSYLVANIA.

OIL-COOLED TRANSFORMER.

Application filed November 8, 1920. Serial No. 422,465.

To all whom it may concern:

Be it known that I, ROBERT V. BINGAY, a citizen of the United States, residing at Pittsburgh, in the county of Allegheny and

5 State of Pennsylvania, have invented certain new and useful Improvements in Oil-Cooled Transformers, of which the following is a specification.

This invention relates to transformers and 10 particularly to transformers cooled by a

circulating liquid such as oil. Such transformers are usually placed in a tank containing the cooling oil which is heated by the transformer and transfers this heat to 15 the outer portion of the tank. The cooling oil is also an insulator and in order to preserve the oil and maintain its insulating properties it has been found desirable to protect it against contact with the outer air.

20 The object of this invention is to provide a transformer containing means that will retain the oil out of contact with the surrounding atmosphere and at the same time permit of expansion and contraction of the 25 oil due to temperature changes.

In the embodiments of the invention shown in the drawings,

Fig. 1 is an elevational view of a transformer tank and expansion tank in connection therewith,

Fig. 2 is a similar view of a modified form, and

Fig. 3 is a similar diagrammatic view illustrating a system adapted for a plurality of tanks.

In the embodiment of the invention shown in Fig. 1 a transformer tank K on a base B contains the transformer and cooling oil O. The tank K is filled with the oil O up to 40 the under surface of the cover C to give

extended cooling contact and to restrict the area of contact of oil and air, the whole tank being oil and air tight. To permit expansion of the oil when heated expansion

45 tank E is provided for instance standing on the base B beside the tank K and connected thereto by pipe P having the three-way cock 9 to close the pipe in both

directions or open a connection between the tanks E and K or to close the connection to tank K and open the bottom of tank E to discharge the oil therefrom. The pipe P and tank E are oil and air tight

50 and when the transformer is connected in circuit it heats the oil O which expands

an amount dependent in general upon the temperature rise of the oil, compressing the gas or air in the tank E and raising its pressure correspondingly. Upon disconnection of the transformer and cooling of 60 the oil the gas pressure in tank E will force the oil back into tank K to maintain the latter always full, and it is to be noted that at no time is there any communication with the outer air.

65 An overheating of the oil O and resultant excessive rise in pressure may be taken care of by the safety blowoff W of the tank K or a safety valve V may be provided on tank E to relieve the pressure. The pressure gage S may also be provided in connection with the tank E and an oil level gage L and air introducing means A comprising for instance a cylinder D containing a drying agent such as calcium chloride 70 and having a pump or pump connection at its outer end to force in air.

75 Under normal conditions of operation the apparatus of this invention will retain the transformer oil sealed against escape and 80 against contact with the outer atmosphere so that the liquid cooling system is hermetically sealed and a circular float member R may be provided to float on the surface of the oil in tank E to further restrict the contact with the air or gas contained in the system. The tank K when cool may be just completely filled for instance to a level 10 or an overflow of the oil through pipe P into tank E may be permitted to establish 85 its own level such as 11 in the tank E or this level may be pumped to any desired point such as 12 and even back up in pipe P by pressure through the pump connection A.

90 If with cool oil the oil pressure at the top of tank K is substantially atmospheric then the gas pressure in tank E will be atmospheric for level 10 of the oil or for level 11 or 12 it will be that of the corresponding level in tank K, for instance a few pounds above atmospheric. When the oil expands the gas pressure increases as its volume decreases and this increased pressure together

95 with that due to the increased head of oil in tank E will be transferred by pipe P to the oil in tank K and when the transformer is in operation the oil O will be under pressure.

100 The tank E instead of resting on the trans-

former base may, where convenient, be mounted in elevated position for instance on top of the transformer cover C as shown in Fig. 2 in connection with the tank E', pipe 5 P' and cock 20, and its operation here will be substantially similar to that in Fig. 1, the gas pressure and its changes being, however, less in this elevated position for a given expansion of the oil so that the pressure 10 variations on the oil in the tank K will be reduced for a given size of expansion tank. These variations would be still further reduced by a higher elevation of the expansion tank and the reduction of the pressure in 15 the expansion tank below atmospheric for instance to a value sufficient to give atmospheric pressure at the top of tank K.

Where there are a number of transformers as indicated in diagram in Fig. 3, the 20 oil supply of all of these transformers may be connected to a single expansion tank preferably placed at an elevated position and acting as a common receptacle for the expansion from all of the transformers. 25 This system has the advantage not only of saving a separate tank for each transformer but also of giving a more nearly constant, average pressure in all of the tanks. The tank E'' of this system will have its pipes 30 P₁, P₂, P₃, etc., provided with control cocks 31, 32, 33, etc., so that any transformer may be disconnected without affecting the others.

The connection of pipe P to the transformer tank K is preferably made at an 35 extreme top point so that air or gas in the tank will be carried over into the expansion tank E and will not remain trapped in the main tank above the level of the pipe opening. While in the foregoing illustrations 40 of the operation of the expansion system the oil pressure at the top of the transformer tank when cool has been assumed as substantially atmospheric it may in the tank of this invention be below atmospheric so that 45 the subsequent pressure on the hot oil at the top of the tank will be more nearly atmospheric.

In the expansion system of this invention the oil is kept out of contact with the 50 atmosphere so that moisture is excluded and oxygenation of the oil is prevented and the oil is preserved indefinitely. Under normal operation the system requires no attention and after severe overheating and over pressure it is only necessary with the tank of Fig. 1 to pump in air or gas to replace that 55 exhausted by the safety valve. With the expansion tank in raised position the air pump A may be replaced by automatic 60 means operating to admit air when the pressure drops below the atmospheric. The expansion apparatus is simple and inexpensive and easily adaptable to differing conditions of transformer installations and while the 65 invention has been described in connection

with specific embodiments thereof, it is not confined thereto but is intended to cover such modifications thereof as fall within the scope of the appended claims.

I claim:

1. In an expansion system for air cooled transformers the combination with a main transformer tank, of a non-expansile tank receiving the overflow from said main tank and having a rigid closed top for trapping and holding a gas above the surface of said overflow and preventing outside air from having access to the surface of the overflow during the expansion of oil in said main tank.

2. In an expansion system for air cooled transformers the combination with a plurality of main transformer tanks, of a single non-expansile tank receiving the overflow from all of said main tanks and having a rigid closed top for trapping and holding a gas above the surface of said overflow and preventing outside air from having access to the surface of the overflow during the expansion of oil in said main tanks.

3. In an expansion system for transformer tanks the combination with a main tank, of an auxiliary non-expansile expansion tank connected therewith and adapted to lower the pressure in the main tank to below atmospheric when cool and permit it to rise above atmospheric during the heating of the oil in the main tank.

4. In an expansion system for air cooled transformers the combination with a main transformer tank, of a non-expansile tank receiving the overflow from said main tank and having a rigid closed top for trapping and holding a gas above the surface of said overflow and preventing outside air from having access to the surface of the overflow during the expansion of oil in said main tank, and means for exhausting gas from said expansion tank when the gas pressure therein exceeds a predetermined amount.

5. In an expansion system for air cooled transformers the combination with a main transformer tank, of a non-expansile tank receiving the overflow from said main tank and having a rigid closed top for trapping and holding a gas above the surface of said overflow and preventing outside air from having access to the surface of the overflow during the expansion of oil in said main tank, and means for introducing air into said expansion tank.

6. In an expansion system for air cooled transformers the combination with a main transformer tank, of a non-expansile tank receiving the overflow from said main tank and having a rigid closed top for trapping and holding a gas above the surface of said overflow and preventing outside air from having access to the surface of the overflow during the expansion of oil in said main

tank, and a member floating on the surface of the overflow in said expansion tank and moving up and down therewith to protect the surface of the oil from contact with the 5 gas above it.

7. In an expansion system for transformers the combination with a main transformer tank, of an auxiliary tank connected thereto completely closed for holding a gas 10 compressed by the expansion of oil in the main tank and preventing the outside air from having access to the surface of the oil, the oil and gas being hermetically sealed against the outside atmosphere during normal 15 operation.

8. In an expansion system for transformers the combination with a main transformer tank, a rigid non-expansible auxiliary tank connected thereto completely 20 closed for holding a gas compressed by the expansion of oil in the main tank and preventing the outside air from having access to the surface of the oil, the oil and gas being hermetically sealed against the outside 25 atmosphere during normal operation.

9. In an expansion system for transformers the combination with a main transformer tank, of an auxiliary tank connected thereto completely closed for holding a gas compressed by the expansion of oil in the 30 main tank and preventing the outside air from having access to the surface of the oil, the oil and gas being hermetically sealed against the outside atmosphere during normal operation, and means permitting the 35 escape of gas above a predetermined pressure.

10. In an expansion system for transformers the combination with a main transformer tank, of an auxiliary tank connected 40 thereto completely closed for holding a gas compressed by the expansion of oil in the main tank and preventing the outside air from having access to the surface of the oil, the oil and gas being hermetically sealed 45 against the outside atmosphere during normal operation, means permitting the escape of gas above a predetermined pressure, and means permitting the admission of gas.

ROBERT V. BINGAY.
